UNITED STATES PATENT OFFICE.

GEORGE E. CLARK, OF WINDSOR LOCKS, CONNECTICUT, ASSIGNOR TO GEORGE P. CLARK COMPANY, OF WINDSOR LOCKS, CONNECTICUT, A CORPORATION OF CONNECTICUT.

ELEVATING-TRUCK.

1,174,685.

Specification of Letters Patent.

Patented Mar. 7, 1916.

Application filed February 24, 1914. Serial No. 820,541.

To all whom it may concern:

Be it known that I, GEORGE E. CLARK, a citizen of the United States of America, residing in the town of Windsor Locks, county of Hartford and State of Connecticut, have invented certain new and useful Improvements in Elevating-Trucks, of which the following is a specification.

This invention relates to an improved elevating or lifting truck. The truck which is known in the art as an elevating truck or lifting truck is shown generally by such a patent as that to Gledhill, #790,495, May 23, 1905.

The object of the invention is to provide in such a truck improved means connected with the handle of the truck for operating the elevating mechanism.

Another object of the invention is to provide in such a truck improved means to operate the elevating mechanism by the handle, said means constructed and arranged so that it is not necessary to connect and disconnect the handle therewith at each 25 complete operation in order to give the handle the necessary freedom for manipulating the truck in the desired manner.

Another object of the invention is to provide a cable connection between the handle 30 and the elevating mechanism having a universal joint connection with the handle to operate the elevating mechanism, by the movement of the handle.

Another object of the invention is to provide an improved means for locking the platform of the truck in elevated position in a positive manner.

Another object of the invention is to provide, in a truck of the class mentioned, improved mechanism combined with the means for locking the platform in elevated position operable to conveniently release the lock when desired.

Another object of the invention is to provide in combination with the means for locking the platform in elevated position, an improved safety device which will prevent accident from a careless release of the lock or careless or accidental lowering of the 50 platform.

Another object of the invention is to provide a lock for the platform in elevated position which is automatically released by manipulating the handle, together with a safety device operable to lock the platform

in elevated position, when the operator fails to lower the platform in a careful manner.

Other objects of the invention will appear in the detailed description and annexed claims.

For the purpose of illustrating one preferred embodiment or one manner of carrying out my invention, reference is had to the accompanying drawings in which:

Figure 1 is a side elevational view of a truck embodying my invention, with the rear portion broken away and indicating the platform in lowered position. Fig. 1^a is a side elevation of the rear portion of the truck not shown in Fig. 1, a small part however, being shown in both figures. Fig. 2 is a plan view of the assembled truck, certain parts being broken away to better show the elevating mechanism thereunder. Fig. 3 is a vertical longitudinal sectional view through the front half of the truck with the rear portion broken away, showing the elevating mechanism in some detail, with the platform in raised position. Fig. 3^a is a vertical longitudinal sectional view of the rear portion of the truck not shown in Fig. 3, a small part, however, being shown in both figures. Fig. 4 is a sectional view taken on the line 4—4 of Fig. 5. Fig. 5 is a front elevation detail view of the platform lock. Fig. 6 is a vertical elevation showing a detail of the elevating mechanism. Fig. 7 is a sectional view taken on the line 7—7 of Fig. 6. Fig. 8 is a sectional view taken on the line 8—8 of Fig. 6.

Referring to Figs. 1 and 1^a, the truck comprises a main frame 3 mounted on two wheels at the rear and one wheel suitably swiveled at the front. At each of the four corners of the main frame there is provided an eccentric gear pivotally mounted and arranged to engage the teeth of a rack 8, mounted at the four corners of the superimposed platform 4. These four gears are each provided with a cam 15 (see Fig. 8), which may be integral with the gear casting and which is adapted to bear against a suitable surface 16 on the casting of the rack 8. The outline of each cam 15 corresponds to the pitch line of the gear 7, and each surface 16 against which the cam bears, corresponds with the pitch line of the rack 8. By reference to the figures, it will be seen that if the platform 4 is moved horizontally, the rack 8, one on each corner

of the platform, will engage its corresponding gear 7 and cause the latter to turn. This will operate to turn the cam 15 and raise the platform 4 on a vertical incline as the platform moves horizontally. In this elevating operation the parts all move with rolling friction only. Such an elevating mechanism has been described and shown in detail and claimed in the co-pending application filed Sept. 9, 1913, by William F. Irrgang, Serial No. 788,795. The elevating mechanism is shown here as a type of elevating which may be used in combination with my improved parts to be described. The invention, broadly, is not limited to any specific type of elevating means to cause the platform to be raised vertically when the platform is moved horizontally, as many other types might be used in the combinations of parts as claimed, without departing from the scope of the invention.

The invention herein relates particularly to the mechanism for moving the platform horizontally. The mechanism for this purpose comprises a cable 20 (see Fig. 3) preferably made of steel wires. An angle bracket 21 is fastened rigidly to a cross brace of the platform 4, preferably at the middle of said cross brace, as indicated in Figs. 2 and 3. The outwardly extending arm of this bracket is provided on its lower surface with teeth to engage corresponding teeth in a pivoted arm 22. This arm 22 has a longitudinal slot provided therein and a bolt is adapted to pass through a hole in the outer end of the bracket 21 and through the slot in the arm 22. A nut on the bolt engages the edges of the slot. In this manner the arm 22 may be adjusted longitudinally with respect to the bracket 21 and any slack or adjustment in the cable 20 may be taken up conveniently. The arm 22 is pivoted to a holding device 23. This holding device 23 is made up of an open ended cone shaped piece, into the small end of which the cable 20 is passed. The end of the cable is then unraveled and molten lead is poured on the unraveled end of the steel wires to enlarge the end of the cable. With this construction, referring to Fig. 3, the cable 20 will not under any circumstances pull out of the holding device 23. A holding device 24 similar to device 23 is provided at the other end of the cable 20, as shown in Fig. 3 and the same kind of a connection is made with the device 24 and the cable 20 as already described. The cable 20 passes between the depending prongs of a fork shaped guiding means 25 (see Fig. 3). This guiding means is fastened to a cross brace of the platform 4 and prevents lateral movement of the cable 20. At the middle of the front cross piece of the platform 4, there is provided a bell shaped opening through which the cable 20 passes. This bell shaped opening

is preferably open at the bottom, having depending prongs corresponding to the guiding device 25. By this structure the cable 20 is free to move vertically as long as it extends under the platform 4 but it is not free while under platform 4, to swing laterally. By providing bell shaped opening 26 at the front of the platform the cable 20 is free to swing and move in all directions as soon as it leaves the bell shaped opening.

The holding device 24 has extending forwardly two vertically distanced arms through which a pin 6 is adapted to pass to make connection between the holding device 24 and the handle 1. The handle 1 of the truck is pivoted immediately above the swiveled front wheel of the truck at the point 2, as shown. The lower end of this handle as shown comprises an inverted T-shaped casting at one corner of which pivotal connection is made to the truck as at 2, and at the other corner of which a horizontally pivoted rod 27 is mounted. The wheel is swiveled to the truck by means of a suitable casting having depending ears to receive the wheel, which casting is mounted in the main frame 4 by a bearing equivalent to a fifth wheel device. The horizontally pivoted rod 27 is held in place between two ears of the casting by means of pivot pins 5. The rod 27, shown in Figs. 2 and 3 may always rock or turn on its horizontal pivot pins 5 with respect to the handle casting but must in all other respects move therewith. The pin 6 passing through the holding device 24 pivots device 24 to the rod 27 which in turn is pivoted as described. The holding device 24, by means of pin 6, is, therefore, free to be moved laterally, and by means of the rod 27 to which the pin 6 is connected, is free to swing vertically. Therefore, the device 24 holding the outer end of the cable 20, is in effect connected to the handle 1 by means of a universal joint.

Referring to Fig. 3, it will be seen that if the handle is swung counter-clockwise on the pivot 2, the cable will be drawn to the left and thus move the platform 4 to the left for the elevating operation. The handle which is connected with the cable 20 as described, operates with a bell-crank leverage to move the platform 4, forwardly. After the platform has been moved sufficiently to elevate it to the desired point it is desirable to lock the platform in elevated position so that the handle 1 may be used to draw or steer the truck without interfering with the elevating mechanism and this is done without the necessity for connecting or disconnecting the cable 20 with the handle at each complete elevating and lowering operation. At the corners of the front cross piece of the platform 4, two

hook shaped arms 30 are pivoted. The outer ends of these arms 30, as shown in Fig. 5, are provided with shoulders or hook shaped portions to engage, each on a vertical abutment on one of the castings 31, fastened at each side to the main frame. These castings may be cast or otherwise connected to frame 3, as by the threaded bolts shown in Fig. 1. Since the arms 30 are pivoted at their inner ends, their own weight will cause them to drop whenever possible. An inclined cam surface 60 (see Fig. 4) is provided on each casting 31 on which the arms 30 ride until they arrive vertically above the abutment before mentioned. A flange 31^a is provided for each cam surface to cooperate with the side face of the main frame 4 to make a recessed path for the arms 30 as they move to locked position. The platform is now in the desired elevated position and the hooks at the outer ends of arms 30 drop into position to engage the vertical abutments before mentioned on castings 31, and prevent the platform which, in this position is designed to carry a heavy load, from being lowered. In this operation the handle is lowered to the position indicated in Fig. 3. With the platform thus locked, the handle 1 may be raised to draw the truck and steer it as desired. When the platform is raised and the handle is raised, the weight of the pivoted holding device 23 and the cable 20 causes the latter to sag vertically between the guiding members 25 and the sides of the bell shaped opening 26. The cable is thus kept ready for use but entirely out of the way, with no possibility of it swinging laterally under the truck to contact with any of the other parts of the truck or with objects on the floor.

When it is desired to release the lock, the handle 1 is lowered and the platform 4 is pulled forwardly a slight amount until the hooks at the ends of members 30 engage a shoulder on the upper end of the pivoted latch 34. This latch is pivoted as shown in Fig. 4, to swing in a slot in the casting and normally occupy the full line position. The handle 1 is raised and the pivoted device 34 as it turns on its pivot causes the hook portion of the lock 30 to ride over the vertical abutment on the end of casting 31, without engaging therewith, and onto the cam surface 60. The latch 34 in this operation moves to the dotted line position in Fig. 4, but after the hook 30 is delivered to the surface 60 the latch returns by gravity to its full line position. The platform is lowered to the position shown in Fig. 1 by gravity as soon as the lock is released.

The handle 1, which is in the lowering operation held by the operator to brake the descent of the platform, may snap out of the hand of the operator when a heavy load is on the platform. For this contingency a de-

vice is provided to automatically lock the platform in elevated position or in practically the same position in which the platform is when the handle is accidentally or carelessly released. This locking device is best shown in Figs. 1^a and 3^a. It comprises a casting 41 fastened to the main frame of the truck and having provided therein as shown, an inclined slot, the upper surface of which is provided with teeth 42 and the lower surface of which is provided with uniform rolls 43. A lever 40 is pivoted to a cross brace of the platform 4 and has at its lower end a downwardly extending pivoted dog 44. This dog is so shaped and pivoted, as indicated in Fig. 4, that if the platform 4 is lowered at a certain speed, the dog will remain out of engagement with the teeth 42 but will, as the lever 40 is lowered, ride up and down over the rolling surface 43 without engaging the teeth 42. If, however, platform 4 starts to drop quickly, the dog 44 in riding over the rolls 43 on the lower surface of the slot, will engage one of the rolls 43 with such force as to be thrown upwardly and the dog will thus engage one of the teeth 42. These teeth are so shaped that they will hold the dog therein as soon as it engages in one of them. This holding operation is aided by the fact that the weight of the platform forces the single tooth of the dog into the engaged tooth of the teeth 42. The platform will thus be automatically locked in elevated position almost immediately after the handle is released. In order to lower the platform from this position it is necessary for the operator to take hold of the handle 1 and pull the platform forwardly, and thus the lever 40 and dog 44, enough to allow the dog 44 to drop from its engagement with one of the teeth 42. The platform may then be lowered provided the speed is not increased beyond the degree predetermined by the construction of the safety device.

I am aware that cushioning devices have heretofore been used with lock releasing means in elevating trucks to control the speed of the platform's descent. An automatically operated locking device having the function of the one here shown I believe to be broadly new. In this application such a device is claimed in combination with the other improved features of my truck. In U. S. Letters Patent #1,102,871, granted to me July 7, 1914, I claim the device broadly, and in other combinations.

I have shown in combination with the elevating mechanism heretofore described, a convenient means for preventing the platform from tipping, due to unevenly placed loads thereon. This means includes at each corner of the truck, a depending flange 50 (see Fig. 6), which flange is integral with the casting of the rack 8. An inclined slot

51 is provided at the lower corner of this flange, having its lower end closed and its upper end open. A pin 52 integral with the casting of the gear 7 is adapted to enter slot 51 as the gear is turned and the rack 8 and the flange 50 move in an incline upwardly. Another flange 9 is integral with the casting of the rack 8 and is constructed to extend vertically downwardly and then horizontally below the hub of the gear 7. The flange 9 is so shaped that as platform 4 moves upwardly, one edge of the flange 9 will be in continual engagement with the lower part of the hub of the gear 7 and thus be in effect a hook which will prevent the platform from tipping. Since there are 4 of these hold down hooks, one at each corner of the platform, the latter can not tip or lift off the main frame 3. The platform moves on an incline upwardly to such an extent that the flange 9 finally leaves its engagement with the said hub but at, or a little before this time, the pin 52 enters the slot 51 and by means of the flange 50, the pin 52 thereafter prevents any tilting of the platform. If the hook ends of flanges 9 were long enough to hold the platform down at all times, the lower ends of the flanges would not, in the structure shown, clear the floor as much as desired. For this reason the flange 50 and pin 52 are provided to co-operate with flange 9.

While I have shown and described one preferred embodiment for the purpose of illustrating the manner in which it may be carried out, I do not desire to limit my invention to the one form shown and therefore have broadly claimed certain features and combinations of the invention.

40 What I claim is:

1. A truck comprising a wheel supported platform, a handle connected to one of the wheels for steering the truck, means to elevate the platform with respect to the wheels, 45 and a universal jointed connection between said means and handle.

2. An elevating truck comprising a frame and a superimposed platform, means to convert a horizontal movement of the platform 50 into a vertical movement with respect to the frame, a steering wheel, a handle pivotally connected therewith, a flexible cable connected to the handle with a universal joint at a distance from its pivot point and connected to the underside of the platform at a distance from its front edge, all constructed and arranged so that the platform may be lifted with respect to the frame when the handle is swung downwardly on its pivot.

60 3. An elevating truck comprising a frame supported on wheels, a platform, a handle pivoted to one of the steering wheels to steer the truck, means to elevate the platform from the frame, a cable having a pivoted 65 connection with the handle for lateral and

vertical swinging movements and connected to operate said elevating means by movement of the handle, a lock independent of the elevating means, constructed to hold the platform in elevated position, and means to automatically release said lock, operable by 70 movement of the handle.

4. A truck comprising a wheel supported frame, a platform thereon, a handle pivoted to one of the wheels for steering the truck, 75 means to elevate the platform from the frame, a cable connected to the handle at a distance from its pivot with a universal joint and connected to operate said elevating means by movement of the handle, a lock to hold the platform in elevated position, said lock constructed to operate to lock whenever the handle is lowered to a predetermined point, and means operable to automatically release said lock when the handle 80 is lowered to another predetermined point 85 and then raised.

5. A truck, comprising, a wheel supported frame, a platform mounted thereon, a handle pivoted to one of the wheels for steering the truck, means to elevate the platform from the frame, said means being operable by a device connected at all times with the handle and platform, an automatically releasable lock operable by the handle, all constructed and arranged so that a downward movement of the handle to a predetermined point will lock the platform in elevated position, and a further downward movement of the handle will operate the lock to release the same when the handle is raised to an elevated position, whereby the platform may be raised and locked in elevated position by one downward sweep of the handle and may be automatically released and lowered by a combined downward and upward sweep of the handle. 100

6. A truck comprising a wheel supported frame, a platform thereon, a handle pivoted to one of the steering wheels to steer the truck, means operable to elevate the platform from the frame, a cable connection between the handle and the platform arranged to operate said elevating means, said cable connected to the handle at all times, an automatically operable lock constructed to hold the platform in elevated position when the handle is lowered to a predetermined point, 110 said cable being connected to the handle by a universal joint, whereby the handle may operate to elevate the platform and lock it in elevated position whenever lowered while turned horizontally at any angle to the longitudinal dimension of the truck. 115

7. A truck, comprising, a wheel supported frame, a steering handle therefor, a platform mounted thereon, means operable from the handle to elevate the platform from the frame by longitudinal movement of the former, a hook-shaped locking device 125 130

pivoted to the platform, a member on the frame formed with an inclined portion to guide said locking device upwardly as the platform is elevated and a shoulder engageable by said locking device when the platform has been lifted to a predetermined position, and a pivoted dog within said member engageable by the locking device on continued upward movement of the platform, said dog arranged to be moved by the locking device as the platform is lowered to carry the locking device over said shoulder, whereby the platform may be automatically locked in its lifted position and released for lowering by manipulation of the steering handle. 15
